COP WINDING MACHINE

Wilhelm Reiners, Gladbach-Rheydt, Gustav Kahlisch, Rheydt, and Stefan Fürst, Gladbach-Rheydt, Germany, assignors to W. Schlafhorst & Co., Gladbach-Rheydt, Germany, a corporation of Germany

Application June 1, 1939, Serial No. 276,779
In Germany June 8, 1938

2 Claims. (Cl. 242—27)

This invention relates to a device for equalizing or increasing the thread tension at the point of the cone of the cop in the course of formation. It is known that, in spite of the winding spindle running at uniform speed, the thread tension decreases slightly precisely at this point owing to the much smaller circumference, with the result that a number of thread layers are produced which are not organically connected with the other windings of the cop and consequently easily slip off. It is known that many proposals have been made for equalizing and increasing the thread tension, some of which proposals are ineffective and others very complicated.

The invention applies to a cop winding machine, in which a cam cylinder serves for imparting the traverse to the thread, according to a prior proposal. The cam groove in the cylinder has a bend in the region of the front reversing point, so that the thread travel receives an additional movement and the thread is tensioned. The bend may be a simple one or a multiple one, so that the groove in the region of the front reversing point extends in the form of a serpentine line in such a manner that repeated tensioning and consequently a better equalization is obtained.

Such bends have already been used on the split drums of quick traverse winding frames, but it is evident that such split shapes can only give a different effect because the thread runs on to the winding in an entirely different manner and the solution proposed by the invention cannot come into question at all in such frames. In these known drums the deflection of the slot merely effects a change in the direction of the thread but no change in the thread tension.

Several embodiments of the invention are illustrated by way of example in the accompanying drawing, in which:

Fig. 1 shows in side elevation a thread guiding cylinder which guides the thread in both directions of traverse,

Fig. 2 is a part partial section of the thread guiding cylinder shown in Fig. 1,

Fig. 3 shows a development of the peripheral wall of the cylinder illustrated in Fig. 1,

Fig. 4 shows a thread guiding cylinder for so-called diagonal feed and

Fig. 5 shows a modified form of construction of the cylinder illustrated in Fig. 1.

In all forms of construction the cop 1, during its formation, is rotated in the usual manner by the winding spindle 2, whereas the cam cylinder 3 producing the thread traverse is driven by a separate shaft 4. The ratio of rotation between the shafts 2 and 4 remains constant. The progressive axial feed of the cam cylinder 3 with reference to the winding spindle 2 is effected by some means known for this purpose.

In the construction illustrated in Figs. 1 to 3 the cylinder wall 3 has a groove 5 which guides the thread to and fro once at each revolution. Whereas as the reversing point 6 of the groove 5 at the rear end is normally constructed, it has at the front end a bend 7 which correspondingly influences the thread and increases the thread tension.

In the form of construction according to Fig. 4 the thread guide 8 is displaced to one end of the cylinder 3 and the cylinder itself has a groove 10 the return leg of which is interrupted. Therefore the thread 1, according to a prior proposal, runs back over the cylinder wall owing to the diagonal feed, until it reaches the pin 9, when it is again caught by the engaging groove 11 and again fed forward by the groove 10. The bend 7 in the region of the front end of the guiding cylinder 3 acts in exactly the same manner as in the construction shown in Fig. 1.

In the form of construction illustrated in Fig. 5 the groove 5 has a double deflection or bend 12 in the region of the reversing point, with the result that the thread 1 is twice retensioned, and consequently the tension of the running on thread 1 is better equalized.

What we claim as our invention and desire to secure by Letters Patent of the United States is:

1. In a machine for winding conically nosed cops, a winding spindle, a thread guiding cam cylinder rotatably mounted adjacent said winding spindle, a stationary thread guide positioned so that thread leaving said stationary guide passes part way around said cam cylinder to reach said winding spindle, said cam cylinder having a helical groove closed at the bottom adapted to receive the thread and to guide it to the winding spindle with a traversing movement, said groove having reversing bends at its front and rear limits and both sides of the groove having an additional braking bend near its front reversing bend.

2. In a machine for winding conically nosed cops, a winding spindle, a thread guiding cam cylinder rotatably mounted adjacent said winding spindle, a stationary thread guide positioned so that thread leaving said stationary guide passes part way around said cam cylinder to reach said winding spindle, said cam cylinder having a helical groove closed at the bottom adapted to receive the thread and to guide it to the winding spindle with a traversing movement, said groove having reversing bends at its front and rear limits and a plurality of additional braking bends near its front reversing bend.
